PROCESS FOR DEWAXING AND REFINING
OILSHenry N. Lyons, South Orange, N. J., assignor to
Doherty Research Company, New York, N. Y.,
a Corporation of Delaware

Application April 29, 1929. Serial No. 358,795

2 Claims. (Cl. 196—18)

This invention relates to a process for separating wax from oils, particularly wax distillates and residuum, also the refining of such oils.

In prior processes for dewaxing oils several methods have been employed, all of which require long periods of time or expensive machinery for separating wax. For example, in the "cold-settling" process, previously filtered stock is mixed with naphtha, slowly cooled and allowed to stand until the amorphous wax or petrolatum settles to the bottom of the precipitation tanks. These tanks are usually heavily insulated and provided with cooling coils since approximately four days are required for the settling of the wax before a separation can be made. Furthermore, considerable care must be taken in getting a proper blend between the stock and the naphtha used for dilution. Recently this "cold-settling process" has been considerably improved by the use of centrifugal separators for the removal of the wax from the oil following the chilling step. The centrifugal separator however can operate successfully only on the separation of amorphous wax, so that even now the crystalline wax is separated by previously known methods, as by chilling the wax stock to below 10° F. and then passing it through filter presses. The use of filter presses however entails considerable outlay for the quantity of oil treated, and furthermore requires more labor. In certain cases also it has been found necessary to "double-press" the oil in order to completely free the same of wax.

In attempting to separate crystalline wax from oil by use of a centrifugal separator, after the wax has been precipitated in the oil, it was found that the wax could not be successfully removed from the separator because of the formation of layers of hard wax on the interior of the separator bowl and the accumulation of solid wax in the wax discharge orifices and collecting pans.

An object of the present invention is, therefore, to provide a process and method of operation which will rapidly and efficiently effect the removal of wax from wax-bearing distillates which contain amorphous wax or inhibitors which do not permit the wax to crystallize, and stocks without the use of complicated and expensive equipment.

In accordance with this object, the invention comprises the chilling of the wax stock sufficiently to precipitate the wax therein and then effecting a rapid settling of the wax by a mechanical thickening operation.

Further objects and advantages of the invention will be apparent from the following descrip-

tion taken in connection with the accompanying drawing in which:

The figure is a diagrammatic view largely in vertical section of an apparatus adapted to carry out the various steps of the process. 60

According to the invention, the oil to be treated, which may be crude oil, cut stock, cut distillates or residuum, is passed from storage (not shown) or a decolorizing system described hereinafter, blended with naphtha and introduced through a pipe 2 into an externally insulated heat exchanger 4 wherein the fresh charging stock passes countercurrent to cold dewaxed oil from a later step of the process. In the heat exchanger 4 the fresh charging stock passes 70 through a coil or coils 6 and is finally delivered through a pipe 8 into a mixing chamber 10 wherein the partially cooled oil which has been blended with naphtha or other suitable diluting agent for the purpose of lowering its cold test 75 may be mixed with other oil or additional quantities of diluting agents introduced through a valved pipe 12.

The mixing chamber 10 is heavily insulated as shown and provided with a mechanical stirrer 80 14 and a hopper 16, the latter of which may be used for the introduction of a filter aid such as "filter cel" or such materials as diatomaceous earth, decolorizing clay or fuller's earth. The chamber 10 may be sufficiently large to accommodate a considerable batch for mixing purposes, or the materials introduced through the inlets 8, 12 and 16 may be introduced in the proportions desired so that the mixing chamber is used continuously. The partially chilled oil or mixture of oil and other materials passes from the chamber 10 through the valved pipe 18, and is forced by pump 20 through a valved pipe 21 into and through cooling coils 22 mounted in an insulated chiller 24. This chiller is preferably operated in connection with a refrigerating plant so that either cold brine or ammonia is introduced through a pipe 26 and passed counter-current to the flow of the oil through the coils 22. The cooling agent is withdrawn from the chamber 24 90 through a pipe 28 and conducted back to the refrigerating plant. 95

In passing through the coils 22 the wax containing stock is cooled to a temperature between zero and 10° F., so that the wax, either amorphous or crystalline, is precipitated in the oil. 105

From the coils 22 the chilled oil mixture is delivered through a valved pipe 29 into a bus pipe 30 from which it may be distributed through distributor pipes 32 into a plurality of insulated 110

thickeners 34, only one of which is shown in the drawing. In some cases it may be desirable to mix the filter aid with the oil after it has been chilled. This may be accomplished by passing the oil from the coils 22 through suitable valved piping as shown, into a mixing chamber 33 similar in construction and operation to the mixer 10. From the mixer 33 the oil and filter aid mixture is conducted through the mixer outlet into the pipe 29. When the oil is mixed with filter aid in mixer 33, mixer 10 is preferably by-passed by conducting the precooled oil through a valved pipe 35.

The thickener 34 as shown in the drawing 15 comprises a tank of comparatively large diameter with respect to its depth and is provided with a sloping conical bottom. It is also equipped with a mechanical thickening mechanism comprising a central shaft 36 provided at its upper end with a drive gear 38 and at its lower end with sweeps 40 which upon rotation of the shaft 36 causes the 20 stratification of the oil and wax in the chamber 34 and the movement of the wax toward the center of the chamber. The lower end of the shaft 36 is provided with a short screw conveyor 42 which extends into the wax outlet 44.

The oil-wax mixture delivered through pipes 30 32 enters the thickener near its center and through a slow operation of the sweeps 40 the oil-wax mixture is carried down in the center of the chamber so that the wax is rapidly precipitated and the clarified oil caused to rise around the inner periphery of the thickener and overflow into an annular trough 46. The separated 35 oil collected in the trough 46 is conducted by a pipe 48 and a pump 50, through a pipe 52 into the heat exchanger 4, where the oil passes in heat-exchange with fresh charging stock as previously referred to. The separated oil is finally delivered through a pipe 54, and passed to storage or to a reducing still.

The separated wax passing through the outlet 44 contains somewhat more oil than is usually found in filter press wax; therefore it is conducted by means of a screw conveyor 56 into a second thickener 58, constructed and operated in substantially the same manner as the thickener 34 described above. The thickener 58 however need not be as large in diameter as the thickener 50 34, since the materials introduced therein contain much larger proportions of solid materials to be separated. The thickener 58 may be construed sufficiently large to take the wax discharge from several of the thickeners 34. The separated 55 oil collected in the trough 46 of separator 58 is passed through a pipe 60, pump 62, pipe 64, and pipe 66 either into the heat exchanger 4 or to storage as desired. The wax delivered from this second thickener is conducted to storage for 60 further treatment and purification in which the filter aid or clay is separated from the wax.

The thickeners 34 and 58 are preferably covered as shown and also heavily insulated. In constructing an apparatus for a large dewaxing plant, the thickeners may be made of concrete and built in the ground so as to provide for small heat losses, or cooling coils 68 may be mounted in the insulation material so as to maintain a comparatively low temperature. The thickener 58 70 may be constructed in a similar manner as shown, and both thickeners are preferably provided with manholes 70.

In carrying out the process with certain stocks in which the difference in specific gravity between the oil and its wax content is small, it is

proposed to mix with the oil in the mixing chamber 10, a quantity of filter aid such as "filter cel" or clay, the particles of which will form nuclei for the precipitation of wax in the coils 22 and separators 34. In such a case the filter aid causes the formation of comparatively large particles of wax and therefore gives a much more rapid separation of the oil in the separators 34. When the addition of filter aid is delayed until the wax has been precipitated in the oil by adding the filter aid in the mixer 33, the wax particles attach themselves to the particles of filter aid and thereby separate more easily than the wax would alone.

The invention further includes a combined process of decolorizing and dewaxing oils in a single operation. In accordance with this procedure the residuum or wax distillate to be treated is introduced into the chamber 10 through the pipe 12, and therein mixed with from 15 to 30% (preferably 20%) of 100-mesh clay introduced through the hopper 16. The oil-clay mixture thus formed is conducted through the pipe 18, and passed by pump 20 and a valved pipe 72, through a heater 74 wherein the oil-clay mixture is raised to a temperature of about 460° F. From the heater the oil-clay mixture is conducted through a pipe 76 into a baffled vapor separator 78 in which the moisture content of the mixture is allowed to escape through a vapor pipe 80. The oil and clay-mixture passing to the bottom of the 105 separator 78 is conducted by a pipe 82 and pump 84 through a cooling coil in a heat exchanger 86, and finally through a valved pipe 88 into the pipe 2.

During this operation the valves in pipes 2, 8 and 21 are closed and the valves in pipes 88, 35 110 and 29 are left open.

The oil-clay mixture introduced into the pipe 2 from pipe 88 now passes through the heat exchanger 4, pipe 35, refrigerating coils 22 and finally into the separators 34. In the coils 22 the 115 oil and clay mixture is cooled to a temperature sufficient to precipitate the wax content of the oil onto the particles of clay. In the chambers 34 the oil is separated from the wax and clay in the manner previously described. This combined 120 decolorizing and dewaxing procedure has many advantages, chief of which are the maintenance of the oil and clay mixture without separation of the clay during the whole operation, and the ease of separating both the clay and wax from 125 the oil without expensive filters or centrifuges, or the use of high pressures. During this operation, diluting naphtha may be introduced with the oil or through the valve in pipe 2.

My present methods lubricating stocks which 130 are subjected to contact filtration with decolorizing clays must be passed through filter presses in order to remove the clay from the oil. In the present process and in accordance with the present invention the clay is much more efficiently and rapidly separated from the oil by the mechanical action in the separators 34. If desired the separated clay may be filter-pressed or steamed to remove the small amount of oil it may 135 contain.

In adopting the present invention for use in plants for dewaxing oils, the principal part of the equipment necessary outside that already contained in the plant, will be the mechanical separating units 34 and 58 which are inexpensive 140 to construct and easy to operate.

Having thus described the invention in its preferred form, what is claimed as new is:

1. An apparatus for the treatment of petroleum oil with clay, comprising a heater, a vapor 150

separator and a refrigerating unit, means for passing a mixture of oil and clay through said heater and into said vapor separator from the latter of which water vapor is permitted to escape, 5 means for passing the oil-clay mixture from said separator through said refrigerating unit to precipitate the wax in the oil, and means for separating the wax and clay from said oil comprising a settling chamber equipped with mechanical thickening elements adapted to effect the 10 rapid separation of the oil.

2. The process of refining and dewaxing lubricating oil stocks, which comprises mixing the oil

stock to be treated with a refining clay, heating the mixture in a confined stream to a temperature sufficient to vaporize any water contained in the mixture, passing the heated mixture into a vapor separating chamber from which the vaporized water is permitted to escape, cooling the remaining oil-clay mixture to a temperature sufficient to precipitate the wax in the mixture, and separating the clay and precipitated wax from the oil by a mechanical thickening operation. 80 85
